DRILLING APPARATUS

Walter T. Caldwell, Enid, Okla., assignor to The
George E. Falling Supply Company, Enid, Okla.,
a corporation of Oklahoma

Application July 27, 1938, Serial No. 221,531

9 Claims. (Cl. 255—22)

This invention relates to apparatus for drilling earth formations and particularly to a portable unit including a derrick, a rotary for actuating a string of drill pipe, mechanism for selectively applying pressure on the drill pipe, a hoisting mechanism for handling the drilling string, a packer unit, and other necessary mechanisms used in drilling operations.

Units of this character must have a high strength weight ratio and be exceptionally compact to permit of portability and conveyance to remote fields of operation as in taking of cores or drilling shot-holes for use in seismic surveying in the prospecting for oil, gas, and the like.

While the parts of the apparatus must be compact, they must be arranged so that one mechanism will not interfere with another mechanism, or with running in and withdrawal of the drilling string.

It is, therefore, a principal object of the present invention to provide a unit of this character having a high strength weight ratio which is compact in arrangement and capable of rapid, efficient drilling of earth formations.

A further object of the invention is to provide an improved mounting of the pressure control mechanism so that it may be readily moved to and from an out-of-the-way position with respect to the rotary, thereby leaving a clear working space about the rotary when running in and pulling the drilling string, running casing, and performing other operations incidental to drilling.

A further object of the invention is to provide power operated means for moving the pressure control mechanism into and out of position, and which is actuated independently of the power required in operating the pressure control mechanism when it is in operative position and engaged with the drilling string.

Further objects of the invention are to provide simple and highly efficient multispeed connections between the power unit and the hoisting and rotary mechanisms.

In accomplishing these and other objects of the invention, as hereinafter pointed out, I have provided improved details of structure, the preferred form of which is illustrated in the accompanying drawings, wherein:

Fig. 1 is a plan view of a portable drilling unit constructed in accordance with the present invention and showing the pressure control mechanism in retracted position.

Fig. 2 is a longitudinal section through the unit on the line 2—2 of Fig. 1, showing the pressure

control mechanism being moved to retracted position.

Fig. 3 is an end elevational view of the unit, the rotary being shown in section to better illustrate the driving connection therefor and the pressure control or feed mechanism being shown in operative position relatively to a drilling string which is indicated in dotted lines.

Fig. 4 is a horizontal section on the line 4—4 of Fig. 3.

Referring more in detail to the drawings:

1 designates the rear portion of a motor vehicle chassis including a frame 2 having its rear portion mounted on wheels 3 which are driven through a drive shaft 4. The opposite end of the frame is supported by the usual steering wheels (not shown) and carries the power unit for operating the shaft 4, as in conventional automotive practice.

The frame 2 supports a platform 5 on which is mounted a power unit 6, which may consist of an ordinary internal combustion engine arranged transversely of the platform and having a multiple speed transmission 7 operating a driving member 8. The driving member 8 may consist of a sprocket as shown, to drive chain belts 9 running over a sprocket member 10 on a shaft 11 which is operatively connected by means of a flexible coupling 12 with a multi-speed transmission 13 located alongside the power unit 6 and arranged so that its driving shaft 14 and driven shaft or power output 15 extend transversely of the platform.

The shaft 11 is supported on the respective sides of the sprocket member 10 in spaced bearing brackets 16 and 17 that are anchored on the platform. The driven shaft 15 is supported at one end by the housing of the transmission 13 and at its opposite end in a bearing bracket 18 carried on the platform at the side opposite the bearing brackets 16 and 17.

Slidably splined on the shaft 15 are spaced clutch members 19 and 20 having teeth 21 and 22 adapted to respectively engage corresponding teeth 23 and 24 on the hubs 25 and 26 of sprocket members 27 and 28, the sprocket members 27 and 28 being rotatably mounted on the shaft 15 but adapted to be connected therewith upon engagement of the respective clutches as later described.

Mounted on the sides of the platform, adjacent the rear edge thereof, are posts 29 and 30 having bearings 31 and 32 at their upper ends pivotally supporting a derrick or mast 33. The derrick 33 includes spaced legs 34 and 35 having adjustable foot members 36 and 37 adapted to engage mud

sills or the like 38 when the derrick is in erect position. The derrick also includes legs 39 cooperating with the legs 34 and 35 to support the usual crown pulleys (not shown), and which 5 suspend the tackle mechanism for handling the drilling string through a hoisting mechanism 40, later described. The derrick is thus mounted on the platform so that it may be swung forwardly of the vehicle to horizontally overlie the mechanism on the platform when in transport position. When the derrick is moved to erect position, as shown in Fig. 2, it is rigidly secured by suitable clamps 41 and 42 that are attached to a downset portion 43 of the frame and which clampingly 10 engage the legs 34 and 35.

The hoisting mechanism 40 includes a spooling drum 44 which is operated to rotate in either direction by sprocket members 45 which are driven from the sprocket members 27 through a 15 chain belt connection 46. The hoisting mechanism also includes a cathead 47 which is selectively driven through the operating mechanism of the hoist as in customary practice. The hoisting drum is thus mounted so that the axis thereof 20 extends parallel with the axes of the driving and driven shafts 11 and 15 and with the power unit 6, so that it may be directly driven therefrom at any one of a plurality of speeds either forward or reverse that are provided in the respective 25 transmissions 7 and 13. The hoisting drum is mounted on the platform so that it is spaced forwardly of the rear edge a sufficient distance to provide ample floor space 48 within the derrick for convenience of the drillers in making up and 30 breaking the joints of the drill pipe incidental to running in and withdrawing the drilling string.

The part of the frame constituting the floor space 48 preferably projects to the rear of the wheels 3 and carries depending brackets 49 suspending the down-set portion of the frame to mount a rotary platform 50 that is positioned below the level of the platform 5. Carried on the platform 50 is a rotary 51 including a collar 52 aligning with an axial opening 53 in the platform 50 and having a radial flange 54 secured to the down-set portion of the frame by fastening devices such as bolts 55. Rotatably mounted within the collar on suitable antifriction bearings 56 is a driving sleeve 57 carrying a tapered slip seating ring 58 for mounting slips 59, the slips 59 having seats 60 adapted to drivingly engage the kelly rod of the drilling string to effect rotation thereof upon operation of the driving sleeve.

The driving sleeve 57 has a ring gear 61 which 55 meshes with a pinion 62 fixed to a shaft 63 rotatably journalled within a trunnion 64 extending laterally of the collar 52, later described. The outer end of the shaft is rotatably supported in spaced bearing brackets 65 and 66 fixed to the platform 50 as shown in Figs. 1 and 3. Fixed to the shaft 63 between the bearing brackets is a sprocket member 67 aligning with the sprocket member 28 previously mentioned, and which is driven therefrom through a chain belt connection 68 operating through an opening 69 in the platform 5, Fig. 1.

The clutches 19 and 20 may be operated by any suitable mechanism but are here shown as controlled by push and pull rods 70 and 71 extending longitudinally of the side of the platform 5 and slidably supported at the rear ends in a bracket 72. The opposite ends of the rods are pivotally connected to the arms 73 and 74 of bell-cranks 75 and 76 respectively, the bell-cranks being 75 mounted on a common pivot 77 carried on the

platform adjacent the clutch member 26. The other arm 78 of the bell-crank 76 is pivotally connected, as at 79, with a shifting yoke 80 having engagement with the clutch 26. The other arm 81 of the bell-crank 75 is connected through a 5 link 82 with a rocker arm 83 pivotally mounted, as at 84, on the platform 5 and connected with a shifting yoke 86 operatively engaged with the clutch 19. The push and pull rods are actuated adjacent the drillers' station by hand levers 87 10 and 88, Figs. 1 and 3.

In drilling certain formations, it is desirable to exert a downward pressure on the drilling string to promote cutting action of the drill bit and in drilling through other formations, particularly when the drilling has progressed to a substantial depth, it may be desirable to relieve pressure of the drilling string upon the bit. The unit therefore includes a pressure operated mechanism 89 for selectively applying pressure through 20 the drilling string or to relieve pressure of the drilling string on the bit as now to be described.

Extending from the rotary collar 51 on the side opposite the trunnion 64 is a trunnion 90 and pivotally mounted on the respective trunnions are 25 cylinders 91 and 92 of the pressure control mechanism. In the illustrated instance the lower ends of the cylinders are shown as having lugs 93 provided with arcuate seats 94 engaging the trunnions and which are retained by caps 95 extending 30 around the opposite side of the trunnions and secured by cap-screws or the like 96. The cylinders are retained in operative position on the trunnions by nuts or equivalent retainers 97 which are threaded on the outer ends of the 35 trunnions. The upper ends of the cylinders are connected by a yoke 98 having a connecting portion 99 curved forwardly to provide a rearwardly opening recess 100 to accommodate the drilling string. The cylinders are provided with pistons 101 and 102 carried on piston rods 103 and 104 movable through stuffing boxes 105 and 106 closing the upper ends of the cylinders. The projecting ends of the piston rods extend through sleeves 107 and 108 on arms 109 projecting radially from 45 a slip supporting collar of a gripping device 110. The piston rods are rigidly secured to the sleeves 107 and 108 and are guidingly supported to move in a perpendicular direction upon actuation of the pistons by guide rods 111 and 112, fixed to the arms 109 in forwardly spaced relation with respect to the cylinders and having their lower ends slidably journaled in bearing openings 113 provided in the connecting yoke 98.

The collar 110 rotatably mounts a gripping 55 device 114 that is retained therein against relatively axial movement and which is provided with gripping devices 115 adapted to be moved into gripping engagement with the kelly rod of the drilling string.

A pressure medium is supplied to the respective ends of the cylinders to selectively act against the upper or lower sides of the pistons through flexible connections 116 and 117 which are connected to a four-way valve 118 having connection through conduits 119 and 120 with the intake and discharge connections of a pump 121.

The pump 121 is mounted on the platform 5 and is operated by means of a chain 122 running over a sprocket 123 on the shaft 11. It is thus 70 obvious that the discharge and intake connections of the pump may be selectively connected with the respective ends of the cylinders so that pressure may be built up upon the lower or upper sides of the pistons. When the pressure is act- 75

ing upon the upper sides of the pistons, pressure is applied to the drilling string through the gripping device to promote cutting action of the drill bit as it is being rotated by the rotary mechanism. 5
5 When the pump pressure is applied to the under side of the pistons, the pistons are raised to support the drilling string, thereby relieving weight thereof upon the drilling bit so as to control the cutting action when penetrating soft, cavy formations. 10

In running in and pulling the string, it is necessary to move the pressure control mechanism out of alignment with the rotary mechanism. This is accomplished by swinging the pressure control unit on the trunnions so that it is passed through an opening 124 of the platform to be positioned therebelow, the opening in the platform being normally closed by trap doors 125 and 126 hinged to the side edges thereof as indicated at 127 and 20 128 so that they may be moved to and from covering relation with the opening. When the pressure unit is in retracted position and the door is closed the platform space below the derrick is entirely free and clear of obstructions and provides ample space necessary in breaking and making up of the joints of the drill string. 25

In order to move the pressure unit on its pivotal mounting, I provide a hydraulically actuated cylinder 129 having one end pivotally supported, 30 as at 130, to a bracket 131 depending from the frame of the vehicle as shown in Fig. 2. Slidably mounted in the cylinder is a piston 132 carrying a piston rod 133 reciprocable through a stuffing box 134 in the head of the cylinder. The projecting end of the piston rod is pivotally connected with an ear 135 projecting from the cylinder 92 by a pin 136 extending through a yoke-shaped head 137 on the piston rod and through the ear 135. A fluid pressure medium is selectively admitted to the respective ends of the cylinder through flexible connections 138 and 139 leading to a four-way valve 140 which is connected with the intake and discharge connections 141 and 142 of a pump 143. The pump 143 may be located 40 on the platform 5 adjacent the pump 121 and operably connected with a sprocket 144 on the shaft 11 through a chain belt connection 145.

In using a drilling unit constructed and assembled as described, it is moved to the location 50 of drilling as an ordinary motor vehicle with the pressure control cylinders supported under the platform, with the trap doors 125 and 126 in closed position, and with the derrick supported horizontally on its pivotal mountings 31 and 32 55 with the upper end extending forwardly of the vehicle. Upon reaching the drilling location, the derrick is erected and secured in perpendicular position by the clamps 41 and 42, and the foot members 36 and 37 are adjusted against supporting sills. The doors 125 and 126 are opened 60 and the pressure control mechanism is raised to operative position over the rotary. This is effected by starting the power unit 6 to drive the pump 143, the valve 140 being adjusted so that the discharge of the pump is connected with the cylinder 129 through the flexible conduit 139 to establish pressure against the bottom of the piston. When the pressure control mechanism is 65 in perpendicular position the valve 140 is adjusted so as to retain pressure in the cylinder 129. The pump may then be shut down by provision of a suitable clutch. 70

The drilling string is suspended by the tackle mechanism from the crown pulleys so that it passes through the gripping device 114 and 75

through the slips 59 of the rotary. The drilling string is actuated by engaging the clutch 20 with the hub 26 of the sprocket member 28, the transmissions 13 and 7 having been manipulated to select the desired speed of rotation. The chains 5 68 drive the sprocket member 67 and rotate the shaft 63 to effect rotation of the slip carrier through the ring gear 61. If desired the slips of the gripping device may be moved into gripping engagement with the drilling string and the 10 pump 121 actuated so that upon proper adjustment of the valve 118 pressure will be admitted through the conduits 116 to the upper sides of the pistons. This will effect downward movement of the 15 piston rods to exert downward pressure of the 20 drilling string upon the drill bit.

When it becomes necessary to pull the drilling string, it is raised through the hoist 40 upon engagement of the clutch 19 with the hub 25 of the 25 sprocket member 27 so as to remove the kelly rod from driving relation with the rotary. The drilling string below the kelly rod is supported on the rotary by the usual spider as in conventional practice and the kelly rod disconnected. The kelly rod may then be removed from the gripping 30 device 114 whereupon the pressure control mechanism may be moved to retractive position below the platform upon actuating the valve 140 so as to apply pressure medium to the cylinder 129 through the conduit 138. When the pressure control device is passed through the opening in the platform the doors are closed, providing ample space for the operators in removing, or running in of the drilling string, adding sections of drill pipe, or performing other necessary operations. 35

From the foregoing it is obvious that I have provided a drilling unit which is of compact arrangement and that the pressure control mechanism is readily moved to and from operative position, and when out of operative position is retracted below the platform in an out-of-the-way position leaving the platform space for use of the operators upon closing of the trap doors. It is also obvious that the power for the pressure control mechanism is independent of the power used in moving the mechanism to and from operative position. 45

What I claim and desire to secure by Letters Patent is: 50

1. In a drilling apparatus, a platform, a trap door in the platform, drilling mechanism carried on the platform including drill pipe rotating mechanism, a pressure actuated mechanism for axially feeding the drill pipe, and means supporting said feeding mechanism on the platform for movement from a position in registry with the axis of said rotating mechanism and through said door to a position substantially below said platform. 60

2. In a drilling apparatus, a mobile platform, drilling mechanism carried on the platform including drill pipe rotating mechanism, pressure mechanism for exerting axial pressure on the drill pipe, a lateral compartment under said platform, and pivotal means mounting said pressure mechanism for movement from an erect position over said rotating mechanism to a reclining position in said compartment. 65

3. In a drilling apparatus, a mobile support having a platform provided with upper and lower offset portions, drilling mechanism carried on the support including drill pipe rotating mechanism mounted upon said lower offset portion of the platform, pressure actuated mecha- 70 75

- nism pivotally supported on said lower offset portion, and means for moving said pressure mechanism on its pivotal support to a reclining position laterally of said lower offset portion 5 and below said upper offset portion.
4. In a drilling apparatus, a platform having an opening therein, a door covering said opening, drilling mechanism carried on the platform including drill pipe rotating mechanism 10 offset below said platform, pressure mechanism for exerting axial pressure on the drill pipe, and means pivotally mounting said pressure mechanism at said offset for movement from a position over said rotating mechanism to a position under 15 said platform and laterally of said rotating mechanism.
5. In an apparatus of the character described, a support, a drill pipe rotating mechanism on the support including a sleeve member, slips carried by the sleeve member, means rotatably mounting the sleeve member for rotation about a fixed axis on the support, a ring gear on the sleeve member, a pinion gear meshing with the ring gear, a shaft rotatably mounting the pinion 20 gear, means for actuating said shaft, pressure actuated means including a gripping device for engaging the drill pipe, and means pivotally supporting said pressure actuated means relatively to the rotating mechanism whereby said pressure 25 actuated means is adapted for movement about the axis of said shaft from a position parallel to said axis of rotation to a reclining position relatively to said rotating mechanism and at substantially right angles to said axis of 30 rotation.
6. In a drilling apparatus, a platform, drilling mechanism carried on the platform including drill pipe rotating mechanism offset below said platform, pressure mechanism for exerting axial pressure on the drill pipe, pivotal means 35 connected with a lower portion of said pressure mechanism and mounting said pressure mechanism for movement from a position over said rotating mechanism to a position under said platform, a hydraulic actuator for effecting movement of said pressure mechanism to and from its respective positions, and means support-

ing said hydraulic actuator below said platform.

7. In an apparatus of the character described, a mobile frame, a drill pipe rotating mechanism having fixed support on said frame, a driving shaft rotatably connected with said rotating mechanism, pressure actuated means including a gripping device for engaging the drill pipe, means pivotally supporting said pressure actuated means relatively to said rotating mechanism whereby said pressure actuated means is adapted 10 for movement about the axis of said shaft from a position in engagement with said pipe to a position laterally of said rotating mechanism, and hydraulic means for shifting said pressure actuated means on its pivotal supporting means. 15

8. In a drilling apparatus, a mobile frame, drill rod rotating mechanism carried on the frame, pressure augmenting means pivotally mounted on the frame, a compartment carried by the frame laterally of said rotating mechanism, a bracket carried by the frame, a hydraulic cylinder pivotally connected with the bracket, a piston in the cylinder, rods connected with the piston and having pivotal connection with the pressure augmenting means, and means for 20 admitting fluid medium to the respective ends of the hydraulic cylinder to effect movement of the pressure augmenting means to and from said compartment.

9. In a drilling apparatus, a mobile frame 30 having offset portions at different elevations, a drill rod rotating mechanism fixed on the lower offset portion, a compartment formed in the upper of said offset portions, pressure augmenting means pivotally mounted over said drill rod 35 rotating mechanism, a bracket suspended from the upper of said offset portions, a hydraulic cylinder pivoted to said bracket, a piston slidable in the cylinder, a piston rod connected with the piston, means pivotally connecting the piston rod with the pressure augmenting means, and means for admitting a pressure medium to the respective ends of the cylinder for moving the pressure augmenting means to and from the compartment. 40
